[57] CLAIM

The ornamental design for a combined stadium cushion and carrying bag, as shown and described.

DESCRIPTION

FIG. 1 is a perspective view of the combined stadium cushion and carrying bag in a folded condition for carrying; FIG. 2 is a front elevational view of the stadium cushion on a reduced scale in an unfolded condition; FIG. 3 is a front elevational view of the stadium cushion on a reduced scale with the seat cushion and the back cushion separated; FIG. 4 is a side elevational view of the stadium cushion on a reduced scale in an unfolded condition, the opposite side being a mirror image of that shown; FIG. 5 is a back elevational view of the stadium cushion on a reduced scale in an unfolded condition; and, FIG. 6 is a perspective view of the stadium cushion on a reduced scale in a partially unfolded condition. The cross-hatching represents conventional fabric and is understood to extend throughout the areas represented. The broken lines represent stitching.
